UNITED STATES PATENT OFFICE.

MICHAEL J. CANTWELL, OF MADISON, WISCONSIN.

DESIGN FOR A CABINET.

SPECIFICATION forming part of Design No. 22,588, dated July 4, 1893.

Application filed March 27, 1893. Serial No. 467,882. Term of patent 14 years.

To all whom it may concern:

Be it known that I, MICHAEL J. CANTWELL, a citizen of the United States, residing at Madison, State of Wisconsin, have invented a certain new, useful, and original Design for a Law-Blank Cabinet, of which the following is a specification.

My invention relates to a new and original law blank cabinet and the object thereof consists in a new, useful and original design for the manufacture of a law blank cabinet or case.

The accompanying drawing represents approximately a front view of the cabinet resting on its base showing a perspective view of the top, one side and the entire front of the cabinet with a drawer at the bottom, below the shelves, partially withdrawn.

A represents a column of compartments and alternate shelves of proportionate size and shape as shown in the drawing.

B represents a column of compartments and alternate shelves placed next to the column A, and of but half the width of column A with some of the compartments of greater depth or perpendicular dimension.

C is a drawer in the bottom of base of the cabinet, the base upon which the main portion of the cabinet rests being somewhat wider than the main portion of the cabinet, the extension being from the front as shown in the drawing.

D represents a curtain partially drawn.

The leading feature of my design consists of two or more columns of compartments compactly placed in a cabinet with curtain for front, together with one shallow drawer at the base, all arranged and in the proportions and of the shape substantially as shown by the drawing and as above described.

What I claim is—

The design for a law blank cabinet as herein described and shown.

Dated at Madison, Wisconsin, March 3, A. D. 1893.

M. J. CANTWELL.

In presence of—

G. J. CORSCOT,
JAS. D. CANTWELL.
